[57] CLAIM

The ornamental design for a display stand, as shown
and described.

DESCRIPTION

FIG. 1 is a front perspective view of a display stand
showing my new design;

FIG. 2 is a rear elevational view thereof;

FIG. 3 is an enlarged sectional view taken on line 3—3
of FIG. 2 showing the top of one of the shelves in
greater detail; and

FIG. 4 is an enlarged sectional view taken on line 4—4
of FIG. 2 showing the bottom of one of the shelves in
greater detail.

The top surface is conventionally flat and unornamented.
